UNITED STATES PATENT OFFICE.

JAMES MAXWELL, SR., OF NEW YORK, N. Y.

DEVICE TO FACILITATE THE PARTING OF HAIR.

1,218,440.

Specification of Letters Patent.

Patented Mar. 6, 1917.

Application filed September 12, 1916. Serial No. 119,789.

To all whom it may concern:

Be it known that I, JAMES MAXWELL, Sr., a citizen of the United States, and a resident of New York, in the county of New York and State of New York, have invented a certain new and useful Improvement in Devices to Facilitate the Parting of Hair, of which the following is a specification.

My present invention relates to devices 10 facilitating the parting of hair on the human head.

The principal objects of my invention are to provide devices which will enable persons to accurately part the hair along an imaginary line or lines and dress the same so that such hair as is at one side of said line will extend in a well defined direction with respect to hair at the other side of said line; to provide devices of the character described 20 which will successfully be used by persons whose eyesight has been destroyed or impaired and who find it impossible to direct a line of vision through the lenses of spectacles or eye-glasses into a mirror in order to 25 visually determine the result of bringing a comb or brush in use, or where the hair to be parted is out of the usual line of vision even when a person is capable of using a mirror; and, to provide devices of the character described 30 which are inexpensive to manufacture, easily manipulated, and which remain in good repair for a considerable length of time.

Another object of my invention is to provide 35 a device to facilitate the parting of hair which may be positioned in engagement with the hair at any portion of the head, and in no way restricted to use with respect to other features of the head, such as the ears.

Further objects of my invention will appear 40 in the following detailed description, taken in connection with the accompanying drawing, forming a part of this specification, and in which drawing:—

Figure 1 is a perspective view of a device 45 embodying my invention shown applied to the hair of a head.

Fig. 2 is a plan view of the device.

Fig. 3 is a transverse sectional view 50 through the device, with the head line diagrammatically represented.

Fig. 4 is an enlarged sectional view on the line 4—4 of Fig. 2.

In the drawing, where similar characters 55 refer to similar parts throughout the views,

A designates a flat strip of material such as celluloid, whalebone, or vulcanized rubber which may be flexed longitudinally but which resists transverse flexure to any material extent; B a similar strip of flexible 60 material; and C, means pivotally connecting said strips of materials A and B with the longitudinal edge of one confronting the longitudinal edge of the other, but permitting either strip to be swung with such edges 65 out of confronting relation for the purpose hereinafter set forth.

Referring first to the strips A and B, one face of each strip is preferably beveled as at 5, at a longitudinal edge, the edges at such 70 bevels being those which are normally in confronting relation as is clearly shown in Fig. 2 of the drawing.

As to the means C, which serve as a coupling between the strips A and B, it may 75 comprise a hinge leaf 6 secured to the strip A as by rivets 7; a hinge leaf 8 secured to a face of strip B as by rivets 9; a coupling member 10 intermediate the leaves 6 and 8 and lying transversely of strips A and B; 80 and, pintles 11 and 12, the former of which connects leaf 6 with coupling member 10, and the latter connecting leaf 8 with said coupling member, the pintles 11 and 12 extending with their axes longitudinally of 85 the strips A and B. When said strips A and B are beveled as at 5, the means C overlies the faces provided with said bevels as is clearly shown in Fig. 4 of the drawing. It is preferred to dispose the means C mid- 90 way of the ends of strips A and B.

When bringing the device into use, the hair is initially brushed or otherwise arranged to extend in the direction substantially parallel to an imaginary line, whereupon the device is placed in engagement with the hair, the faces with which the coupling has connection being outermost. The strips A and B are arranged so that their confronting edges lie longitudinally 100 of the imaginary line where the part is to be made, whereupon one of the strips, in the example shown, that designated B, is raised, the other strip A held so as to conform substantially to the curvature of the head. 105 With the strip B arranged so that its edge does not confront the complementary edge of the strip A, a comb or brush may be used in dressing or arranging the hair to one side of the strip A, as is clearly shown in Fig. 1 110

of the drawing. This is followed by swinging the strip B into engagement with the hair, retaining the hair thus arranged in place, the strip A being swung upwardly 5 exposing the hair to the other side of the imaginary line and enabling the user to comb or brush the hair so as to extend in a well defined direction with respect to that to the other side of the imaginary line. By 10 beveling the strip as at 5, the bristles of a brush, or the teeth of a comb, are guided to engage the exposed hair adjacent the device, facilitating the parting of the hair.

When not in use, the device is compact, 15 and may be easily carried in the pocket, owing to the fact that the means C normally maintain the strips A and B with longitudinal edges in confronting relation one to another.

20 Changes in details may be made without departing from the spirit or scope of my invention; but,

I claim:

1. A device to facilitate the parting of 25 hair comprising in combination, two flat strips of material capable of being flexed longitudinally, and means for pivotally connecting said strips of material substantially midway of their ends, normally disposing the edge of one confronting the edge 30 of the other, but permitting either strip to

be swung with such edges out of confronting relation.

2. A device to facilitate the parting of hair comprising in combination, two flat 35 strips of material capable of being arcuated longitudinally, a face of each strip beveled at its longitudinal edge, and means pivotally connecting said strips of material substantially midway of their ends normally 40 disposing the longitudinal edge of the bevel of one strip confronting the longitudinal edge of the bevel of the other strip, but permitting either strip to be swung with such edges out of confronting relation. 45

3. A device to facilitate the parting of hair comprising in combination, two flat strips of material capable of being arcuated longitudinally, and a coupling pivotally connecting each of said strips with the 50 points of connection between their longitudinal margins.

4. A device to facilitate the parting of hair comprising in combination, two flat strips of material capable of being arcuated 55 longitudinally, a face of each strip beveled at a longitudinal edge, two hinge leaves, one secured at each of said strips at the beveled face thereof, a coupling member, and pintles extending longitudinally of said strips connecting said coupling member and leaves. 60
